(57) **CLAIM**

The ornamental design for a card hanger, as shown and described.

DESCRIPTION

FIG. 1 is a perspective view of a card hanger showing my new design;

FIG. 2 is a front elevational view of the card hanger shown in FIG. 1;

FIG. 3 is a rear elevational view of the card hanger shown in FIG. 1;

FIG. 4 is a left side elevational view of the card hanger shown in FIG. 1;

FIG. 5 is a right side elevational view of the card hanger shown in FIG. 1;

FIG. 6 is a top plan view of the card hanger shown in FIG. 1;

FIG. 7 is a bottom plan view of the card hanger shown in FIG. 1;

FIG. 8 is a front elevational view of a plurality of connected card hangers extending in a generally vertical direction and with the broken line showing for illustrative purposes only and forming no part of the claimed design;

FIG. 9 is a front elevational view of a plurality of connected card hangers extending in arcuate direction; and,

FIG. 10 is a front elevational view of a plurality of vertically extending card hangers supported from a plurality of card hangers extending in an arcuate direction.
